UNITED STATES PATENT OFFICE.

ROBERT ASHWORTH AND ALBERT W. ASHWORTH, OF NEW HAVEN,
CONNECTICUT, ASSIGNORS TO L. T. SNOW, OF SAME PLACE.

WRENCH.

SPECIFICATION forming part of Letters Patent No. 628,218, dated July 4, 1899.

Application filed October 14, 1898. Serial No. 693,552. (No model.)

To all whom it may concern:

Be it known that we, ROBERT ASHWORTH and ALBERT W. ASHWORTH, citizens of the United States, residing at New Haven, in the county of New Haven and State of Connecticut, have invented certain new and useful Improvements in Wrenches, of which the following is a specification, reference being had therein to the accompanying drawings.

10 Our invention relates to wrenches having a pivoted jaw opposite a bearing-surface, and is mainly intended for wrenches intended to grasp a cylindrical body, as pipe-wrenches, although it is also adapted to be used as a 15 nut-wrench; and the object of our invention is to produce a simple and inexpensive wrench of that class with which objects of various sizes can be grasped equally well without changing the location of the fulcrums of the 20 jaws, said wrench being provided with two jaws independently pivoted, but mounted upon the same handle. We attain this object by the construction illustrated in the accompanying drawings, in which—

25 Figure 1 is a side view of a pipe-wrench constructed in accordance with our invention, the adjustable body of the outer jaw being shown substantially parallel with the handle and its gripping-face relatively close to the gripping- 30 face of the inner jaw. Fig. 2 is a longitudinal section of the pipe-wrench in which the adjustable body of the outer jaw is substantially at right angles with the handle and its gripping-face relatively distant from the gripping- 35 face of the inner jaw, although the distance between the parts of the two jaws is the same in both figures. Fig. 3 is a longitudinal section of a nut-wrench, showing our invention applied thereto by having the pivoted jaws slightly modified in form to grasp a polygonal object. Fig. 4 is a perspective view of the pipe-wrench shown also in Figs. 1 and 2. Fig. 5 is a transverse section on line xx of Fig. 1. Fig. 6 is a longitudinal section 40 of a pipe-wrench constructed in accordance with our invention provided with a modified form of pivoted inner jaw. Fig. 7 is a longitudinal section of the wrench with the jaws transposed on the pivot-pins to further increase the capability of the wrench to grasp 45 large objects.

In the drawings, A represents the handle of the implement, the inner end B of which is bent laterally and is slotted lengthwise to obtain two flat branches b, on the inner portion of which is pivoted to said branches upon the pivot-pin c the body d of the longest or outer jaw D. To the outer ends of said branches the inner jaw E is pivoted upon a milled-head pin f, which passes through said branches and has its end screw-threaded for engagement with a screw-tapped hole in one of the branches. The pivot-pin c is similarly headed and screw-threaded. The body d of the outer jaw is preferably slightly tapering, 65 wider at its inner end, to obtain the best form of abutment for the inner face or heel of the pivoted jaw E. The body d of the outer jaw D has a series of perforations d^2 , either one of which is adapted to receive the pivot-pin 70 c, so that the implement is capable of engagement with pipes or other bodies varying greatly in size. The jaw E has also a series of perforations e transversely thereof, all substantially at the same distance from the back 75 or bearing face of said jaw, to also insure the capability of adjustment of the implement.

When the device is intended for use as a pipe-wrench and it is desired to have an inner bearing-surface provided with a large 80 number of interchangeable bearing-teeth, a wheel G may be substituted and pivoted upon the outer bearing-pin f; but if the implement is to be used as a pipe-cutter a cutting-wheel may, as usual, be substituted for the wheel G. 85

In Fig. 7 the location of the jaws is shown transposed and the latter reversed on the pivot-pins, in which position the capacity of the wrench to grasp large objects is further increased. In either position of the jaws the 90 wrench is particularly well adapted to grasp and rotate pipes or other objects located alongside of walls or in other limited locations.

If the implement is to be used as a nut-wrench, the outer jaw D is provided with a 95 flat bearing-face and the inner jaw E is also provided with a flat bearing-face, as shown in Fig. 3.

Having now fully described our invention, we claim—

1. A wrench consisting of a handle having 100 its inner end bent laterally and forked, each

- branch of said fork having two perforations, the perforations in one of the branches being screw-tapped, a removable pivot-pin in each one of said perforations, and upon each 5 pin, a reversible jaw pivotally mounted thereon, the body of each jaw having a series of pivotal perforations, whereby either jaw may be adjusted and reversed in position, substantially as described.
- 10 2. In a wrench the combination of a handle having its inner end bent laterally and forked, each branch of said fork having two perforations, removable pivot-pins in said perfora-

tions, and two oppositely-disposed and transposable jaws pivotally mounted upon said 15 pins, the body of one of said jaws having a series of pivotal perforations, substantially as described.

In testimony whereof we affix our signatures in presence of two witnesses.

ROBERT ASHWORTH.
ALBERT W. ASHWORTH.
